UNITED STATES PATENT OFFICE

171,888

GAME BOARD

Lawrence Goodman, Riverdale, N. Y.

Application April 13, 1953, Serial No. 24,460

Term of patent 14 years

(Cl. D34—5)

To all whom it may concern:

Be it known that I, Lawrence Goodman, a citizen of the United States, residing at Riverdale, in the county of the Bronx and State of New York, have invented a new, original, and ornamental Design for a Game Board, of which the following is a specification; reference being had to the accompanying drawing, forming a part thereof.

The figure is a plan view of a game board, showing my new design.

The game board is of conventional thickness.
I claim:

The ornamental design for a game board, substantially as shown and described.
